CLAIM

The ornamental design for a small sand aggregate splitter as shown and described.

DESCRIPTION

1. Small sand aggregate splitter

1.1: Top

1.2: Bottom

1.3: Front

1.4: Back

1.5: Left

1.6: Right

1.7: Perspective

1.8: Cross sectional

1.9: Exploded

The design relates to a small sand aggregate splitter; its characteristic features include a conically shaped opening at the top that merges into a cylindrical section, which is held by a rounded yoke with a ring-shaped central area, and whereby the cylindrical section abuts a sloping polyhedron body with fourfold symmetry as well as a prominent container at the bottom with four receiving areas whose edges and corners are softly rounded.
